US00D988131S

(12) **United States Design Patent** (10) Patent No.: **US D988,131 S**
(45) Date of Patent: **** Jun. 6, 2023**

(54) CAP	D57,053 S * 2/1921 Ingram et al. D9/452
(71) Applicant: Chubby Gorilla, Inc. , Santa Fe Springs, CA (US)	1,734,372 A * 11/1929 Graham B65D 45/34 215/316
(72) Inventor: Ibrahim H. Aboabdo , Yorba Linda, CA (US)	2,076,549 A 4/1937 Conner
(73) Assignee: Chubby Gorilla, Inc. , Fullerton, CA (US)	2,433,629 A * 12/1947 Howell B65D 51/243 215/305
(**) Term: 15 Years	D165,034 S 10/1951 Van Sciver
(21) Appl. No.: 29/680,038	3,713,528 A 1/1973 Daenen et al.
(22) Filed: Feb. 12, 2019	D229,748 S 1/1974 White
Related U.S. Application Data	
(63) Continuation-in-part of application No. 29/665,474, filed on Oct. 3, 2018, now Pat. No. Des. 907,501, and a continuation-in-part of application No. 29/661,407, filed on Aug. 27, 2018, now Pat. No. Des. 892,623.	3,847,494 A 11/1974 Franklin

CLAIM

The ornamental design for cap, as shown and described herein.

DESCRIPTION

FIG. 1 is a top perspective view of a first embodiment of a cap embodying the new design.

FIG. 2 is a bottom perspective view thereof.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is a top perspective view of a second embodiment of a cap embodying the new design.

FIG. 10 is a bottom perspective view thereof.

FIG. 11 is a front view thereof.

FIG. 12 is a rear view thereof.

FIG. 13 is a first side view thereof.

FIG. 14 is a second side view thereof.

FIG. 15 is a top view thereof.

FIG. 16 is a bottom view thereof.

FIG. 17 is a top perspective view of a third embodiment of a cap embodying the new design.

FIG. 18 is a bottom perspective view thereof.

FIG. 19 is a front view thereof.

FIG. 20 is a rear view thereof.

FIG. 21 is a first side view thereof.

FIG. 22 is a second side view thereof.

FIG. 23 is a top view thereof.

FIG. 24 is a bottom view thereof.

FIG. 25 is a top perspective view of a fourth embodiment of a cap embodying the new design.

FIG. 26 is a bottom perspective view thereof.

FIG. 27 is a front view thereof.

FIG. 28 is a rear view thereof.

FIG. 29 is a first side view thereof.

FIG. 30 is a second side view thereof.

FIG. 31 is a top view thereof.

FIG. 32 is a bottom view thereof.

FIG. 33 is a top perspective view of a fifth embodiment of a cap embodying the new design.

FIG. 34 is a bottom perspective view thereof.

FIG. 35 is a front view thereof.

FIG. 36 is a rear view thereof.

FIG. 37 is a first side view thereof.

FIG. 38 is a second side view thereof.

FIG. 39 is a top view thereof.

FIG. 40 is a bottom view thereof.

FIG. 41 is a top perspective view of a sixth embodiment of a cap embodying the new design.

FIG. 42 is a bottom perspective view thereof.

FIG. 43 is a front view thereof.

FIG. 44 is a rear view thereof.

FIG. 45 is a first side view thereof.

FIG. 46 is a second side view thereof.

FIG. 47 is a top view thereof.

FIG. 48 is a bottom view thereof.

FIG. 49 is a top perspective view of a seventh embodiment of a cap embodying the new design.

FIG. 50 is a bottom perspective view thereof.

FIG. 51 is a front view thereof.

FIG. 52 is a rear view thereof.

FIG. 53 is a first side view thereof.

FIG. 54 is a second side view thereof.

FIG. 55 is a top view thereof.

FIG. 56 is a bottom view thereof.

FIG. 57 is a top perspective view of an eighth embodiment of a cap embodying the new design.

FIG. 58 is a bottom perspective view thereof.

FIG. 59 is a front view thereof.

FIG. 60 is a rear view thereof.

FIG. 61 is a first side view thereof.

FIG. 62 is a second side view thereof.

FIG. 63 is a top view thereof.

FIG. 64 is a bottom view thereof.

FIG. 65 is a top perspective view of a ninth embodiment of a cap embodying the new design.
FIG. 66 is a bottom perspective view thereof.
FIG. 67 is a front view thereof.
FIG. 68 is a rear view thereof.
FIG. 69 is a first side view thereof.
FIG. 70 is a second side view thereof.
FIG. 71 is a top view thereof.
FIG. 72 is a bottom view thereof.
FIG. 73 is a top perspective view of a tenth embodiment of a cap embodying the new design.
FIG. 74 is a bottom perspective view thereof.
FIG. 75 is a front view thereof.
FIG. 76 is a rear view thereof.
FIG. 77 is a first side view thereof.
FIG. 78 is a second side view thereof.
FIG. 79 is a top view thereof.
FIG. 80 is a bottom view thereof.
FIG. 81 is a top perspective view of an eleventh embodiment of a cap embodying the new design.

FIG. 82 is a bottom perspective view thereof.
FIG. 83 is a front view thereof.
FIG. 84 is a rear view thereof.
FIG. 85 is a first side view thereof.
FIG. 86 is a second side view thereof.
FIG. 87 is a top view thereof.
FIG. 88 is a bottom view thereof.
FIG. 89 is a top perspective view of a twelfth embodiment of a cap embodying the new design.
FIG. 90 is a bottom perspective view thereof.
FIG. 91 is a front view thereof.
FIG. 92 is a rear view thereof.
FIG. 93 is a first side view thereof.
FIG. 94 is a second side view thereof.
FIG. 95 is a top view thereof; and,
FIG. 96 is a bottom view thereof.
The broken lines depict portions of the cap that form no part of the claimed design.
